DESIGN FOR A BATH ATTACHMENT FOR BIRD CAGES

Carl W. Johnson, Detroit, Mich., assignor to Sewell Manufacturing Company, Detroit, Mich.,
a corporation of Michigan

Application February 23, 1940, Serial No. 90,443

Term of patent 14 years

To all whom it may concern:

Be it known that I, Carl W. Johnson, a citizen of the United States, residing at Detroit, in the county of Wayne and State of Michigan, have invented a new, original, and ornamental Design for a Bath Attachment for Bird Cages, of which the following is a specification, reference being had to the accompanying drawing, forming part thereof.

ment for bird cages, viewed from above and one side, showing my new design.

I claim:

The ornamental design for a bath attachment for bird cages, as shown.

CARL W. JOHNSON.
